MOTOR TABLE

Percy R. Prosser, Pasadena, Calif.

Application July 24, 1933, Serial No. 682,035
Renewed June 8, 1936

1 Claim. (Cl. 29—86.3)

This invention relates broadly to means adapted to facilitate the removal of the valves of an internal combustion engine.

The present practice of removing the springs of the valves from the detachable heads of gas engines of the overhead valve type, by the use of the conventional hand tools, for the purpose of grinding the valves of such engines, requires considerable labor, patience, and time.

10. The general object of my invention is to provide a device by means of which the valve springs may be conveniently and quickly removed, with little labor, from the detachable heads of overhead valve gas engines, and by means of which 15 the heads may be readily supported in a convenient position for grinding the valves.

Another object is to provide an apparatus of the character stated which is simple in construction, inexpensive, and highly practical and efficient in operation.

Another object is to provide a device adapted to hold a cylinder head and valves, together with suitable tools, and which device is readily movable from place to place as may be required, to the end that the cylinder head and valves may be worked upon.

Another object is the provision of an apparatus constituting a table so constructed and arranged as to permit a cylinder head to assume two positions thereupon and to be maintained in the position selected.

I do not wish to restrict my invention in its broad aspect to a table but in practicing the invention, I provide what may be termed a bench or table mounted upon castors or small wheels, to the end that a mechanic can readily move the bench or table adjacent an automobile from which a cylinder head is to be removed for placement thereon. The present embodiment of the 40 invention, as hereinafter set forth, contemplates the placement of the cylinder head upon the top of the bench or table in such a manner that the cylinder head may assume two positions, one for the removal of the valve springs, and a second 45 position to be assumed when it is desired to remove the valves from the cylinder head for the purpose of grinding the valves, and/or seating the valves to the said head.

With the above mentioned and other objects in view, the invention consists in the novel and useful provision, formation, construction, association and relative arrangement of parts, members, and features, all as shown in a certain embodiment in the accompanying drawings, described

generally and more particularly pointed out in the claim.

Other objects and advantages of the invention will appear hereinafter.

In the drawings:

Figure 1 is a plan view of my invention, with the detachable cylinder head of an overhead valve gas engine supported thereon, in position for removal of the valve spring of one of the valves of the engine, 5

Figure 2 is a front elevation of my invention as illustrated in Figure 1,

Figure 3 is a transverse vertical section of my invention taken on line 3—3 of Figure 2,

Figure 4 is an enlarged fragmentary vertical section of my invention taken on line 4—4 of Figure 2, 15

Figure 5 is a fragmentary plan view of my invention with a section of the table let down so that the cylinder head may be conveniently supported at the front of the table for grinding the valves of the engine, 20

Figure 6 is a fragmentary transverse vertical section of the table of my apparatus taken on line 6—6 of Figure 5, 25

Figure 7 is a perspective of the cylinder head and valve supporting plate,

Figure 8 is a fragmentary vertical section of the valve spring depresser plunger taken on line 8—8 of Figure 4, and, 30

Figure 9 is a longitudinal section of the upper end of one of the valve stems and the valve retainer lock.

Referring with particularity to the drawings, I 35 designate a table comprising a top 2, top supporting frame 3, legs 4, and a bracing frame 5 secured to the legs near the lower ends thereof. Upstanding rails 6 and 7 may be secured to the rear and end edges respectively of the top 2, to prevent objects, such as valve parts, from dropping off said edges of the top. 40

A pair of standards 8 are secured to the top 2 of the table, by bolts 9, near the rear of the top, which standards are formed with bearings 10, in their upper ends, in which are journaled 45 cylindrical ends 11 of a square rock-shaft 12 extending longitudinally of the table or parallel to the front and rear edges of the table top 2. On said shaft 12, a lever 13 is secured adjacent one of the standards 8 by means of a pin 14 and 50 clamp 15, formed in the lever and including a clamp bolt 16. To the rear end of said lever 13 is connected the upper end of a spring 17, the lower end of which spring is connected to a hook 18 secured in the table top 2. The forward end 55

of the lever 13 is connected to the upper end of a rod 16 which extends downwardly through the table top 2 and is connected at its lower end to an arm 29 secured on a horizontal shaft 21 journaled in bearings 22 mounted on the under side of the table bracing frame 5. A foot treadle 23 is secured to the shaft 21 and extends forwardly to a point in front of the table 1 to be depressed by the foot of the operator of my apparatus, as will be hereinafter more fully set forth.

On the square shaft 12 is slidably mounted a depressor arm 24 for depressing a depressor plunger 25, said arm being formed with a square collar 26 which is slidably fitted on said shaft so that said arm may be moved along said shaft from one position to another for the purpose hereinafter set forth. The depressor plunger 25 comprises an annular depressor head 27, stirrup 28 secured at its lower ends to said head, and shank 29 secured at its lower end to the upper end of said stirrup, said shank being formed with a slot 30 extending longitudinally therein to receive the forward end of the depressor arm 24 which is connected to said shank by a pin 31 extended through said end of said arm and through any pair of aligned holes 32 in said shank at opposite sides of the slot 30 therein, which pairs of aligned holes are spaced vertically in said shank. By inserting the pin 31 through different pairs of holes 32 in the shank 29, the arm 24 may be connected at different positions to the shank 29 for adjusting the position of the depressor head 27 to engage the valve spring retaining washers at different elevations in different cylinder heads.

The table top 2 is formed with a hinged leaf 33 extending inwardly from the forward edge of the top in front of the shaft 12, which leaf is hinged at its forward edge, by double-pivot hinges 34, to the front angle iron member 35 of the frame 3 of the table top 2, whereby said leaf 33 may swing into or out of the opening 37 in the table top 2 on the hinge pivots 38 and downwardly in front of the table (Figure 6) or upwardly therefrom on the hinge pivots 39 to be swung into said opening 37 as aforesaid. On cross members 40 of the table top frame 3, at the ends respectively of the leaf opening 37, are formed sockets 41 and 42 near the inner edge of said opening, in either of which sockets may be placed the ends of a rail 43, which, together with the front member 35 of said top frame, is adapted to support a cylinder head in said leaf opening for grinding the valves in said head, when the leaf 33 is swung out of said opening and down in front of the table.

For supporting the valves in the cylinder head while the head is positioned on the table for depressing the valve springs to remove the spring retainer locks, I provide a supporting plate 44 formed with a plurality of upstanding valve supporting bases 45.

The head 27 is provided with an annular recessed portion 27a. This recessed portion is adapted to receive and confine the washer 52 and hence hold the washer in position against lateral displacement when the head 27 is being depressed to in turn depress the washer and its associated spring 53. The diameter of the recess is slightly greater than the greatest diameter of the washer 52.

The operation, uses and advantages of my invention are as follows:

To remove the retainer locks of the valve springs, in a detachable head of an overhead

valve engine by means of my apparatus in order to remove the valve springs, and to support said head, by means of my apparatus, for grinding said valves, the valve supporting plate 44 is first placed on the table top 2 in front of the rock shaft 12 and under the depressor head 27 (see Figures 2 and 4), the head 50 is removed from the cylinder block of the engine and placed upon said plate 44 with the valves resting upon the bases 45, an intake valve and an exhaust valve resting upon each of said bases (Figures 1 and 2); the arm 24 is moved along the rock shaft 12 until the depressor head 27 is directly over the upper end of a valve rod 51, valve spring retaining washer 52 and spring 53 (see Figure 4); the operator then places his foot upon the treadle 23 and depresses the same, whereupon the shaft 12 is rocked counter-clockwise (Figure 3), through the medium of said treadle, shaft 21, arm 20, rod 19, and lever 13, against the tension of spring 17, and the plunger 25, through the arm 24, is depressed until the depressor head 27, passing over the upper end of the valve stem 51, engages the valve spring retaining washer 52 and depresses said washer and the valve spring 53 until the retaining washer split lock 54 is withdrawn from the lock socket 55 in said washer. The lock 54 is then removed by the operator from the annular groove 56 in the valve stem 51, and the operator then releases his foot from the treadle 23, whereupon the treadle, through the medium of lever 13, rod 19, arm 20 and rock shaft 21, is raised back to its normal position and the plunger 25, through arm 24, is likewise raised, by the spring 17, until the depressor head 27 is withdrawn from the valve spring retaining washer 52 and the upper end of the valve stem 51. The operator then removes the retaining washer and the valve spring 53 from the valve stem 51.

The operator then moves the arm 24 along the rock shaft 12 progressively to each of the remaining valves, and the above-described operations are repeated to remove the retaining lock 54 of each remaining valve spring washer 52, so that all of said washers and valve springs may be removed by the operator. When the retaining locks 54, washers 52 and springs 53 are removed from all of the valves, the operator swings the leaf 23 upwardly out of the opening 37 in the table top and downwardly on the hinges 34 in front of the table and the operator then inverts the cylinder head 50, with the plate 44 engaging the bottom of the head 50 and the bases 45 engaging the valves and places the engine head in said opening 37 upon the front member 35 of the top frame 3 and the supporting rail 43 in position for grinding the valves in said head. The valves are then removed and faced, the valve seat reamed, then the valves are ground in the usual manner.

After the valves are ground, the cylinder head is then inverted right-side up and placed upon the table top, resting upon the supporting plate 44; the springs and retaining washers are placed over the valve stems; the retaining washers and springs of the valves respectively are again depressed by the depressor head 27; the retaining locks 54 are placed back on the valve stems respectively in the stem grooves 56; and the depressor head is withdrawn from the retaining washers. The valves being ground, and their springs, retaining washers, and locks being replaced, the cylinder head is then removed from the table and replaced upon the engine block.

The cylinder head is conveniently and easily handled and the valve spring retaining elements and springs of the engine are easily removed and replaced by the use of my improved apparatus, and considerable labor, patience and time are thus saved.

The top 2 is of sufficient size to allow the valve springs and other elements to be definitely positioned thereupon or in trays made for that purpose, to the end that the valves and springs, together with the retaining elements, may be again positioned in the cylinder head and in the same sequence in which they were removed. This is important for proper operation of the engine,

15 as is self-evident.

It is obvious that various changes and modifications and variations may be made in practicing the invention in departure from the particular showing of the drawings without de-

20 parting from the true spirit of the invention.

I claim:

An apparatus as disclosed comprising a table, means for supporting a cylinder head with valves on the rear portion of said table, means on said table for removing the retainer locks, retainer washers and valve springs from the 5 valves and the cylinder head, while said head is supported on the rear portion of said table, said table being formed with an opening in the forward portion thereof immediately forwardly of the position in which said cylinder head is supported on the table for removal of the retainer locks, washers, and valve springs, a leaf hinged to the forward edge of the table normally resting within and closing said opening, but adapted to swing out of said opening and down in 15 front of the table so that the cylinder head may be received inverted in said opening, and means for supporting the inverted cylinder head in said opening for grinding the valves.

20 PERCY R. PROSSER.
